DOUBLE-FACED MASK

Filed Aug. 5, 1948

UNITED STATES PATENT OFFICE

2,513,019

DOUBLE-FACED MASK

Everett J. Grady, New York, N. Y.

Application August 5, 1948, Serial No. 42,697

3 Claims. (Cl. 2-206)

1

My invention relates to face masks and more particularly to a plural or double faced mask adapted to be worn over a person's face and suitably supported such as by ear engaging means or members, ties or an elastic band extending over the ears and around the back of the head and having a plurality, preferably two, of face portions or masks in different or contrasting caricatures, facial expressions or grotesque characteristics, such as smiling, laughing, happy or otherwise on one face or side, and sad, crying, disconsolate or otherwise on the other face or side.

The invention also comprehends a double faced mask comprising a backing simulating or having the outline or shape of a person's head and a plurality of masks or face portions of substantially the same shape but with different or contrasting facial expressions thereon at the front and each scored or foldable vertically at the center and having eye openings, and a nose opening or portion through which the nose of the wearer may project to facilitate support as well as permit proper breathing, each face portion, another face portion or other face portions, being secured at or to the front of the backing at or over half sections of each at each side of the fold line, so that any one of said face portions may be exposed to view by folding back the other face portions against the backing for selectively and interchangeably using any one of said contrasting masks or face portions.

With the above and other objects in view, my invention consists in the arrangement, combination and details of construction disclosed in the drawings and specification, and then more particularly pointed out in the appended claims.

In the drawing,

Figure 1 is a front elevation of my plural or double faced mask showing one mask,

Figure 2 is a view similar to Figure 1 with another mask exposed,

Figure 3 is a section taken on the line 3-3 of Figure 1, with the mask shown in Figure 1 exposed in the full line position and the mask shown in Figure 2 exposed in the dotted line position,

Figure 4 is an enlarged fragmentary plan view with the parts exploded to show the manner of assembly thereof.

Referring to the drawing in detail, the plural or double faced mask of the present invention comprises a base or backing 10 consisting of a main blank or sheet of relatively stiff but bendable material such as cardboard, heavy paper, cloth or other suitable material simulating or

having the shape or outline of a person's head looking at the front or face and including side projections or extensions forming ears 11.

Disposed at the front of the backing 10, are a plurality, preferably two, of masks or face portions 12 and 13 consisting of auxiliary foldable or hinged sheets of the same outline or shape and of the same or similar material as the main backing or sheet 10 and having corresponding ear forming side projections or extensions 14. Masks or face portions 12 and 13 are printed or ornamented with different or contrasting facial expressions thereon at the front, and each scored or foldable vertically at the center as indicated by the fold lines 15 from top to bottom bisecting the same from the top of the head through the bottom of the chin. All of the blanks or sheets 10, 12 and 13 are provided with registering eye openings 16 to expose the eyes of the wearer and provide for vision, while a nose receiving opening or portion 17 is provided centrally therebeneath and therebetween, through which the nose of the wearer may project to facilitate support as well as permit proper breathing.

The fold lines 15 also bisect or extend centrally across the hair 18 and forehead 19 between eyebrows 20 above the eye openings 16, across nose opening 17, mouth 21 and chin 22. The masks or face portions 12 and 13 are of different or contrasting caricatures, facial expressions or grotesque characteristics, the mask 12 being shown by way of example as sad, disconsolate, or sour and the mask 13 as smiling, laughing or happy, although any different or contrasting characters or characteristics may be depicted thereon.

At one side of the fold line 15, the left hand side or half of the sheet of mask 12 is secured, attached or anchored to the corresponding left half of the front or face portion of the backing sheet 10 as seen in Figures 3 and 4, in any suitable manner flat against and in permanent association therewith, while the other portion or half of the sheet or mask 12 at the other side of the fold line 15 is free of backing sheet 10 to fold flat against either side or half thereof.

At the other side of the fold line 15, the other or right hand side or half of the sheet of mask 13 as also seen in Figures 3 and 4, is similarly secured or anchored to the corresponding right half of the front or face portion of the backing sheet 10 likewise flat against and in permanent association therewith so that the outstanding inner portions or free halves or sides of both masks or face portions 12 and 13 are hinged and may swing or fold on the fold lines 15. These free

halves or sides, namely, the right hand side or half of one and the left hand side or half of the other, are secured together back to back, flat one against the other the same as the other halves thereof are secured to backing 10, such as by adhesive, with the eye and nose openings 16 and 17 all registering.

In this way, the hinged portions may be folded against one half of mask 13 as shown in solid lines in Figure 3 to expose the mask 12 as seen in Figure 1, or against the other half as indicated in dotted lines in Figure 3 to expose the mask 13 as seen in Figure 2. Of course, additional masks may be provided by securing additional masks or face portions to the opposed back 15 faces of the foldable or free halves of masks 12 and 13, such as an additional mask thereto and exposed therebetween.

Paper clips or tabs such as Scotch tape may be used to hold the foldable section in folded positions at either side for exposing the different masks. Suitable means may also be provided to attach the mask to the head of a person over the face, such as ear engaging means or members shown as ties or an elastic band 23 to tie or engage over the wearer's ears and around the back of the head. As shown, the ends 24 of the ties or band 23 are extended through openings 25 in parts 10, 12 and 13 in or adjacent the projections or extensions 11, and 14 forming the ears of the parts 10, and 12 and 13, respectively, and anchored in any suitable way as by pins 26 which may also be used to hold the collapsed or folded sections down against the backing 10 and flat anchored portions of masks 12 and 13. Thus, a plurality of masks with contrasting or different characteristics, facial expressions, caricatures or otherwise, is provided, each being selectively and interchangeably usable as described.

I do not mean to confine myself to the exact details of construction herein disclosed but claim all variations falling within the purview of the appended claims.

What I claim is:

1. A double face mask comprising a backing sheet shaped to conform to the full face outline of a person's head, a pair of sheets each bearing a facsimile of a face and having the same shape as that of said backing sheet, said latter sheets being folded along the vertical median line thereof, the portions on the opposite sides of said median lines of said facsimile bearing sheets being cementitiously secured to the front surface of said backing sheet, the other portions of said facsimile bearing sheets being secured together in back-to-

5 back relationship to provide a flap pivotally disposed upon said backing sheet whereby said flap when folded flat against said backing sheet in one direction will expose one facsimile of a face, and when folded in the other direction will expose another facsimile of a face.

2. A face mask comprising a backing sheet, a pair of facsimile bearing sheets each formed to conform to the shape of said backing sheet and folded along the vertical median line thereof, portions of said facsimile bearing sheets on opposite sides of the fold lines thereof being secured to the front surface of said backing sheet, the other portions of said facsimile bearing sheets being secured together in back-to-back relationship to form a pivotable flap whereby, when said flap is pivoted in one direction flat against said backing sheet, one of said facsimile bearing sheets will be exposed, and when said flap is pivoted in the other direction, the other of said facsimile bearing sheets will be exposed.

3. A face mask comprising a backing sheet shaped to conform to the full-face outline of a person's head, a central nose receiving aperture 25 formed in said backing sheet, a pair of facsimile bearing sheets each having a shape conforming to that of said backing sheet and formed with a central nose receiving aperture, said facsimile bearing sheets being folded along the vertical 30 median lines thereof, a portion of each of said facsimile bearing sheets on opposite sides of the fold lines thereof being secured to the front surface of said backing sheet, the other portions of said facsimile bearing sheets being secured together in back-to-back relationship to form a pivotable flap, and means secured to the opposite side edges of said backing sheet and of said facsimile bearing sheet portions carried thereby adapted to support the mask on a person's face 35 whereby, one of said facsimile bearing sheets will be exposed when the flap is pivoted in one direction against said backing sheet, and the other of said facsimile bearing sheets will be exposed when the flap is pivoted in the opposite direction.
